UNITED STATES PATENT OFFICE.

HENRY C. BAINBRIDGE, OF BROOKLYN, NEW YORK.

DESIGN FOR ENVELOPES.

SPECIFICATION forming part of **Design No. 11,686**, dated **March 16, 1880.**

Application filed January 23, 1880. Term of patent 7 years.

To all whom it may concern:

Be it known that I, HENRY C. BAINBRIDGE, of the city of Brooklyn, in the county of Kings and State of New York, have originated and 5 produced a new and original Design for Envelopes, of which the following is a description, reference being had to the accompanying drawings, in which—

Figure 1 represents a back view of an envelope of my design, showing it closed. Fig. 10 2 is a back view of the same, showing the seal-flap open.

The distinguishing characteristic of my design is, that the bottom flap, *a*, and the seal-flap *b*, when both are closed, as shown in Fig. 15 1, have their edges *a'* and *b'* extending in parallel lines diagonally across from side to side of the envelope, with an opening or space be-

tween them, so that both of the said edges are visible, and portions of the side flaps, *c c*, are 20 visible through the parallel diagonal opening between the said edges, the envelope thus being made to present a very unique appearance.

I claim—

The design for an envelope in which the edges of the bottom flap and seal-flap extend diagonally across the envelope from side to side thereof in parallel lines, with an opening or space between them, substantially as herein 25 30 shown and described.

HENRY C. BAINBRIDGE.
